CLAIM

The ornamental design for a housing for a telephone set, as shown and described.

DESCRIPTION

FIG. 1 is a front elevational view of a housing for a telephone set showing my new design in closed relationship;

FIG. 2 is a side elevational view thereof, the side opposite being a mirror image;

FIG. 3 is a rear elevational view thereof;

FIGS. 4 and 5 are respectively top and bottom plan views thereof; and

FIG. 6 is a front elevational view of the telephone housing opened for use, with the front of the handset mounted vertically in the housing.

Fig.4.
